HEEL BUILDING MACHINE

William Roderick Barclay and Hubert Boothroyd, Leicester, England, assignors to United Shoe Machinery Corporation, Borough of Flemington, N. J., a corporation of New Jersey

Application March 7, 1939, Serial No. 260,356
In Great Britain March 17, 1938

5 Claims. (Cl. 12—50)

This invention relates to heel building machines of the type in which heel lifts are assembled in a mold and held under pressure while heel building nails are driven into them by power operated nail drivers.

When high heels are being built, long nails must be used and these sometimes cause trouble by being deflected from straight lines while they are being driven.

10 It is known that this trouble can be overcome by previously pricking holes in the assembled lifts, into which holes the heel building nails are driven. This preliminary pricking of the heels insures that the nails will be driven 15 straight, regardless of the height of the heel.

It is an object of the present invention to provide a heel building machine in which is embodied a simple, easily controlled, pricking mechanism capable of use, when required, in connection 20 with the heel building operation and, in its preferred form, capable of being rendered inoperative when it is not needed.

In the illustrated machine the pricking of the heel, prior to the nail driving operation, is provided for by mounting both awls and nail drivers in a manually operable slide which is movable to bring either the awls or the drivers, alternatively, into an operating position in line with the heel assembling mold and between said mold and a power operated driving plunger. According to 25 the invention a safety locking mechanism is provided for preventing the machine from being started when the slide is in such a position that neither the awls nor the drivers are in line with the mold, thus avoiding danger of breakage of the machine, which would certainly occur if the power were applied at such times.

Damage would also occur if it were attempted 30 to drive the awls into a heel after the nails had been driven therein and another feature of the invention resides in the provision of locking mechanism for preventing the nail drivers from being operated before the awls are operated to prick the heel, that is to say, insuring that the 35 machine can be operated only in the proper sequence.

Since low heels, which do not require preliminary pricking, can also be built in the same machine, provision is made for holding part of the 40 above-mentioned locking mechanism in an alternative position so that the machine can be started only when the nail drivers are in line with the mold, in which case the awls are not used at all, and the machine functions as an ordinary heel building machine, the heel building nails be-

ing driven without previously pricking holes for their guidance.

These and other features and advantages of the invention will best be understood and appreciated from the following detailed description of 5 one embodiment thereof when read in connection with the accompanying drawings, in which

Fig. 1 is a right-hand side elevational view of the illustrative machine;

Fig. 2 is a view, partly in section, on a vertical 10 plane extending from front to rear of the machine;

Figs. 3 to 6, inclusive, are side elevational views of various details of the operating and controlling mechanisms, and

Fig. 7 is a view partly in section on a vertical 15 plane extending from side to side of the machine.

The illustrative machine is similar in general construction to that disclosed in United States 20 Letters Patent No. 2,046,443, granted July 7, 1936, upon an application filed in the names of William R. Barclay, Reginald B. Woodcock, and Wilfrid T. Minett, and comprises a frame 11, from the rear of which extends upward a bracket 13 and upon the front of which is an upright post 15. The lower part 17 of the post 15 has a central, vertical bore 19 extending therethrough (Fig. 7) while the upper part of the post 30 consists of two vertical wings, 21 at the left and 23 at the right, which are spaced apart and extend from front to rear of the machine.

Mounted for vertical sliding movement in the bore 19 is a cylindrical actuator plunger 25 carrying at its lower end an upper cam roll 27 which co-operates with a cam 29 mounted on the front end of a driving shaft 31, which extends from front to rear of the machine and is carried by bearings in the frame. A downward extension 40 from the plunger 25 carries a lower cam roll 33 which is positioned vertically below the cam roll 27 and co-operates with the cam 29 at a certain stage in the operation of the machine.

Upon the rear end of the driving shaft 31 is 45 loosely mounted a large pulley 35 which is continuously driven from any convenient source of power and may be coupled to the driving shaft 31, when desired, by a single-revolution clutch controlled by a starting lever 37.

When the machine is stopped, the plunger 25 is lowered and there is a gap between the cam roll 33 and the cam 29, the cam roll 27 being held down by the weight of the plunger and the associated parts. When the clutch is tripped, the 50 55

plunger 25 is raised in the bore 19 and then returned to its lowered position.

The lower part of the post 15 carries a shaft 39 which extends crosswise of the machine. 5 Loosely pivoted on the shaft 39 is a hand lever 43 which extends forward from the shaft and has a hand piece 45 on its forward end. A flat surface 47 on the lever 43 is adapted to engage beneath a pin 49 which is secured in the plunger 10 25 and protrudes through a slot in the right-hand side of the lower part of the post 15. When the hand piece 45 is lifted, the plunger 25 will be lifted until it is stopped by the cam roll 33 coming into contact with the cam 29, thus permitting 15 the operator to see whether or not the correct number of nails are in the nail block of the machine.

The plunger 25 has a forwardly and rearwardly extending diametrical slot at its upper end, in 20 the two side walls of which are cut guideways each comprising an upper horizontal surface 53, a lower surface 55 and a vertical surface 57. The forward part 56 (see Fig. 2) of the said lower surface is at a lower level than the rearward part 58 25 thereof, the two parts being connected by a sloping intermediate part 60. When the plunger 25 is in its lowered position, as when the machine is at rest, the forward parts 56 of the lower guideway surfaces 55 are substantially level with the 30 flat upper surface 59 of a table 61 extending forward from the lower part 17 of the post 15 so that the table 61 constitutes in effect a forward continuation of the guideways in the plunger. A table 63 having a flat upper surface 65 also constitutes, in effect, a continuation of the rearward parts 58 of the lower guideway surfaces 55 in a rearward direction. Some distance above the surfaces 59, 65, there are formed in the wings 21, 23 guideways 67 extending forwardly and rearwardly of the machine and sloping slightly downward toward the front of the machine.

Above the guideways 67, the opposing inner faces of the wings 21, 23 extend upward to edges 69 which are parallel to the guideways 67. From 45 its edge 69, each wing has a downwardly and outwardly extending surface 71.

It will be apparent that between the opposing faces of the wings 21, 23 of the post 15, a forwardly and rearwardly extending channel is presented. 50 In this channel a rectangular slide 73 is mounted to move forward and rearward. Projecting from the sides of the slide 73 are ribs 75 which fit in the guideways 67 and above the ribs are inclined flanges 77 which are arranged 55 parallel to and just above the surfaces 71 of the wings.

The slide member 73 has two vertical bores 79, 81; the bore 79 being the smaller of the two and being behind the bore 81. In the body part of the 60 slide member, the bores 79, 81 have continuous cylindrical surfaces but the slide member also has a depending part, the width of which is less than the diameter of the bore 79 and which is divided by the bores into three depending lugs 83, 85, 87. 65 The arrangement is such that when the machine is at rest, the slide member 73 may slide forward and rearward in the channel between the wings 21, 23. As the plunger 25 rises, parts, at least, of two of the lugs 83, 85, 87 are accommodated in 70 recesses in the plunger 25. One of these recesses is indicated at 89 in Fig. 7.

Each of the bores 79, 81 in the slide member 73 is enlarged at its upper end to form an internal, circular ledge, as indicated at 90 and 91, 75 respectively. Fitted for sliding movement within

the bore 81 and normally resting upon the ledge 91 is a nail block 93 having integral with its top a small boss 95, whose horizontal cross section is substantially the same as that of the tread surface of a heel. Secured to the nail block and extending downward therefrom is a stem 97 terminating at its lower end in a head 99. The nail block 93 has a projection upon its periphery which fits slidably in a vertical groove in the bore 81 and prevents the nail block from turning but permits it to slide vertically. The stem 97 extends through a bore in a circular plate 101 to which are affixed three nail drivers 103 which extend parallel to the stem 97 into holes drilled through the nail block 93. 15

The stem 97 also passes through a cylindrical, cup-shaped member 105 which is vertically slideable in the bore 81 and has a peripheral projection which fits slidably in a vertical groove in the bore 81 to prevent turning movement of the 20 said member 105. The nail-driver plate 101 normally rests within the cup member 105 which has at its lower end two laterally projecting ears 107. When the slide member 73 is in a rearward position, as shown in Fig. 2, these ears 107 are situated on the lower guideway surfaces 55 in the plunger 25, so that when the plunger is lifted, for example, by lifting the nail-showing hand lever 43, the member 105 is also lifted, together with the plate 101 which normally rests on the bottom 30 of the recess in the member 105.

Supported on the ledge 90 in the bore 79 in the slide member 73 is a cover plate 109 and beneath the ledge is a pricker plunger 111 which is vertically slideable in said bore. The plunger 111 35 has a spline 113 which prevents turning movement, and carries three vertical awls 115 which have flat upper ends. At the lower end of the plunger 111 are formed laterally projecting ears 40 similar to the ears 107 at the lower end of the member 105.

Carried in a bearing in a casting 117 secured to the rear of the post 15 is a rockshaft 119 which extends from side to side of the machine and has affixed thereto an upwardly extending lever 121 45 connected to the rear of the slide member 73 by a short link 123. The link 123 is connected to the lever 121 by a pin 125 which may be readily withdrawn to permit the slide member 73 to be removed from the machine.

To the right-hand end of the shaft 119 is affixed a rocking lever 127, of which one arm 129 extends forward and another arm 131 extends rearward. Secured to the arm 131 is one end of a long tension spring 133, the other end of which is secured to a stationary part of the machine at a point near the floor. Pivoted to the arm 129 is a downwardly extending treadle rod 134, the lower end of which is connected to a treadle 135. The arrangement is such that depression of the 60 treadle 135 causes the slide member 73 to be moved forward. The said slide member is returned rearward by the action of the spring 133 when the treadle is released. The forward position of the slide member 73 when the treadle is 65 fully depressed is determined by a lug 137 which engages a stationary stop pin 138 mounted in the casting 117; rearward movement of the slide member 73 is limited by contact of the slide member with an adjustable stop screw 140 carried by the bracket 13.

When the treadle is not depressed, the bore 81 in the slide 73 is substantially coaxial with the bore 19 in the post 15 and the ears 107 at the lower end of the member 105 are accommodated 75

in the guideways in the plunger 25. At this time, the plunger 111 rests upon the table 63. When the treadle 135 is depressed, the slide 73 is moved forward, the ears 107 at the lower end of the member 105 sliding out of the guideways in the plunger 25 until the member 105 rests upon the table 61 and the ears at the lower end of the pricker plunger 111 have engaged in the guideways in the plunger 25. The bore 79 in the slide 10 73 is now substantially coaxial with the bore 19 and the pricker plunger is above the plunger 25.

The machine comprises a pair of upright bars 139, one at each side of the machine, the upper ends of said bars being joined by a beam 141 which supports a presser pad (not shown). The bars 139 may be swung forward about pivots 143 at their lower ends until the bars are substantially vertical and the presser pad is directly above the bore 19. During the rotation of the driving shaft 20 31 under power, the bars are brought down by a toggle arrangement, whereby a pile of heel lifts which have been placed in a mold 145 is compressed, for the driving of nails therein, between the mold and the presser pad.

25 The mold 145 is supported in the following manner. The bracket 13 carries at its upper end a pin 147 on which is pivotally supported the rear end portion of a bracket 149. Two spring-pressed plungers 148 (see Fig. 3) housed in bosses 30 150 on the bracket 149, urge the bracket upward, normally holding it in an intermediate position, shown in Figs. 1 and 2, in which spring-pressed plungers (one of which is shown at 151) carried by a bar 153 bridging the gap between the wings 35 21, 23 prevent further upward movement by engagement with the front end portion of the bracket. If the plungers 151 are pulled forward to disengage them from the bracket, the latter may be swung upward about the pin 147 into an 40 inoperative position, in which it is yieldingly retained by engagement of a spring-pressed detent 155 carried by the bracket 149 in a recess 157 in a stationary bracket 159 secured to the bracket 13. The mold 145 and bracket 149 are held in this position to facilitate cleaning the parts thereunder.

45 The bracket 149 carries a plate 161 having an aperture 163 in which the upper end portion of the boss 95 fits and above the aperture carries the mold 145 which is clamped to the plate 161 by 50 spring-pressed clamping fingers 165 (see Fig. 5), arranged one at each side of the mold and carried by sleeves 167 rotatable in bores in the bracket 149. The mold 145 is of a known type, comprising an upright wall enclosing a heel-shaped 55 space, and has a flange 169 which is engaged by the fingers 165.

The machine as thus far described is intended 60 to be operated as follows. First, a pile of lifts is assembled in the mold 145 and then the bars 139 are swung forward to bring the presser pad over the mold. The treadle 135 is now depressed to bring the slide member 73 into its forward position so that the cover plate 109 and the awls 115 are beneath the mold. The starting lever 37 65 is next actuated to trip the clutch, causing a pricking cycle of operation of the machine during which one complete revolution is imparted to the main shaft 31, the cam 29 lifting the plunger 25 and then lowering it. Since the pricker plunger 70 111 is above the plunger 25, the awls 115 pass up through the cover plate 109 and are driven into the pile of lifts in the mold to form passages into which the nails may be driven. While the plunger 25 is rising, the bars 139 descend, carrying the presser pad downward to compress the

pile of lifts in the mold. As soon as the presser pad engages the lifts, the mold and the bracket 149 are forced downward against the action of the plungers 148 until the plate 161 engages the top 5 of the slide member 73 and the actual compression 10 of the lifts begins; a boss 171 on the cover plate 109 now fits snugly in the aperture 163. As the presser pad rises after the compression is finished, the mold is lifted a short distance by the plungers 148, the boss 171 being disengaged from the aperture 163 and enough clearance being provided between the plate 161 and the boss 171 to allow the slide member 73 to slide rearward.

15 After the shaft 31 has made one complete revolution and come to rest, the treadle 135 is released, whereupon the slide member 73 is moved rearward by the spring 133, bringing the nail block 93 under the mold. Then, the starting lever 37 is again actuated to trip the clutch to give a nail-driving cycle of operations, during 20 which the driving shaft makes one complete revolution and causes nails which previously will have been placed in the nail block 93 by the operator to be driven upward into the holes which have been made in the lifts by the awls during the previous pricking cycle. At the conclusion of the nail-driving cycle, the bars 139 rise to lift the presser pad away from the mold and when the machine comes to rest, the operator swings the bars back into their rearward positions.

25 Provision is made for preventing the machine from being so operated that the nails are driven first and then the awls are operated, in which event damage would be done to the awls and the heel. The starting lever 37 has three arms, of 30 which one, 173, extends upward and forward from a fixed pivot stud 175 and terminates in a handle 177. A second arm 179 extends forward from the pivot stud 175, while a third arm 181 extends rearward and is pivotally connected to the upper 40 end of a link 183, the lower end of which is pivotally connected to one arm 185 of a clutch-tripping lever pivoted at its mid-point upon a pin 189. The clutch-tripping lever also has a rearwardly extending arm 187, to which is pivotally connected 45 an upright link 191 which is urged in a counterclockwise direction, as viewed in Fig. 1, by a spring 193.

The single-revolution clutch is so arranged that when the handle 177 is brought forward to an 50 intermediate position from its extreme rearward position, the link 191 is lowered and a shoulder 195 thereon pulls down an arm 197, allowing the clutch to engage. Further downward movement of the link 191 will cause the shoulder 195 to be 55 disengaged from the arm 197 by co-operation of a cam face 199 upon the link with a stationary pin 201, allowing the arm 197 to rise into such a position that when the driving shaft 31 has completed one revolution, the clutch will be disengaged and the shaft will be stopped. From the foregoing, it may be understood that if the handle 177 is held in front of its extreme rearward position, the machine cannot be started from rest and, similarly, it cannot be started if the handle is in its rearward position and is prevented from moving forward past its intermediate position.

55 Loosely mounted on the rockshaft 119 is an arm 203 which carries at its end an arc-shaped 60 stop piece 205. The arm 203 also has an arcuate hub portion 207 which co-operates with an arcuate hub section 209 formed as part of the rocking lever 127 so that the arm 203 is constrained 65 to turn with the lever 127, except that a small 70 75

amount of play is allowed between the hub portion 207 and the hub section 209, permitting some relative angular movement between the arm 203 and the lever 127. The arm 203 is urged in a 5 counterclockwise direction about the end of the rockshaft 119, as seen in Fig. 6, by a spring 213 connected to a stationary part of the machine, thus taking up the play indicated at 211 in a counterclockwise direction. The arm 203 may, 10 however, move clockwise relatively to the lever 127, against the action of the spring 213, if it is required to do so.

Normally, when the machine is at rest before the commencement of a sequence of operations 15 as outlined above, the slide member 73 is in its rearmost position in engagement with the screw 140 and the handle 177 is in a forward position where it is held by engagement of a pin 215 fixed in the right-hand bar 139 with an upper surface 20 of the arm 179 of the starting lever 37. The starting lever cannot be actuated to trip the clutch until the bars 139 have been swung forward to bring the presser pad over the mold 145. When the bars 139 are in their forward position, 25 the pin 215 is in front of the end of the arm 179 but the starting lever 37 cannot yet be swung rearward because a stop pin 217 upon the arm 173 engages the lower part of the outer face of the arc-shaped stop piece 205. It is only when 30 the treadle 135 has been depressed sufficiently far to bring the slide 73 to its forward position that the pin 217 can pass above the stop piece 205 to free the starting lever for rearward movement to its extreme rearward position, from 35 which it may be moved forward to trip the clutch.

The stop piece 205 thus operates to prevent 40 the machine from being started until the slide has been brought to its forward position and, in this way, prevents the nails from being driven before the awls have been operated to prick the lifts. It also operates to prevent the machine 45 from being started with the slide in an intermediate position, which would result in breakage of the machine.

When the bars 139 have been brought forward and the treadle 135 has been fully depressed, the handle 177 moves back under the action of a spring 208 into its extreme rearward position, 50 from which it may be moved forward to trip the clutch, whereupon the clutch engages and the awls 115 are operated to prick the lifts. Thereafter, the bars 139 move up, but the handle 177 being now in its rearmost position, the arm 179 55 is higher than it was in the beginning and the upper surface of the pin 215 is substantially level with an arcuate surface on the under side of the arm 179. Consequently, if the bars 139 should be allowed to move back, the pin 215 would pass under the said arcuate surface and the starting lever 37 could not be actuated to trip the clutch. Normally, however, the bars 139 will be held forward 60 during the entire sequence of operations.

After the machine has stopped in this intermediate condition, in which the lifts have been pricked but the nails have not been driven, the treadle 135 is released, the stop pin 217 being back of the stop piece 205, whereupon the stop piece 205 moves upward in front of the pin. During this upward movement, the handle 177 cannot 65 be moved forward but when the slide 73 has reached its rearmost position, a part 219 of the stop piece 205 is presented to the pin 217. The part 219 constitutes a cam so shaped that pressure of the pin 217 against it from behind causes the stop piece 205 to be lifted and the arm 263

to be swung relatively to the lever 127 until the pin 217 passes beneath the stop piece, this swinging movement being permitted by the play at 7 211. The starting lever 37 may thus be actuated to trip the clutch when the slide is in its rearmost position, but not until it has reached the rearward limit of its movement. Thus, again the machine cannot be started while the slide 73 is in an intermediate position; after the stop pin 217 has passed beneath the stop piece 205, 10 the latter immediately swings down behind the pin and prevents rearward movement thereof.

As the pin 217 passes beneath the stop piece 205, the handle 177 can be moved forward through its intermediate position, whereupon 15 the clutch is tripped and, the slide 73 now being in its rearward position, the rotation of the driving shaft causes the driving of nails into the pricked holes in the lifts.

The operation of building a heel is now finished and when the machine comes to rest, the bars 139 are allowed to swing back, the pin 215 passing along the upper arcuate surface of the arm 179, and the heel may be removed from the mold. The machine is now in its original start- 20 ing position, with the pin 217 in front of the stop piece 205, and cannot be started again until the treadle 135 has been fully depressed to bring the slide 73 into forward position for the next prick- 25 ing operation.

The machine is equipped with mechanism whereby at the end of the nail-driving cycle, upward movement of the bars 139 causes the heel to be raised to free it from the mold and thereafter rearward movement of the bars causes the heel to be raised still further, so that it can be 30 readily removed from the mold.

This mechanism is shown in Fig. 4 and includes an arm 221 secured to the left-hand end of the shaft 39 and an arm 223 secured to the 40 shaft 39 near the center thereof and having a forward part 225 underlying the head 99 of the stem 97. Loosely mounted on the shaft 39 adjacent to the arm 223 is a bell crank lever 227, 229, of which the upwardly and rearwardly extending 45 arm 227 carries at its end an eccentrically adjustable pin 231. The bell crank lever is urged clockwise, as seen in Fig. 4, about the shaft 39 by a spring 233, such clockwise movement being limited by contact of a lug 235 on the forwardly 50 extending arm 229, with a pin 237 carried by the arm 221. Clockwise movement of the arm 221 is limited by contact of the arm 223 with a stationary stop surface 238 (Fig. 2).

The arm 229 carries at its end a pin 239 on 55 which is pivotally mounted a latch lever having a forwardly extending hand piece 241 and a downwardly extending arm 243 carrying two hooks 245, 247, one below the other. These hooks are adapted to co-operate with a pin 249 carried 60 by the arm 221, the latch lever being urged counterclockwise about the pin 239 by a spring 251.

The bracket 13 carries a lug 253 in which is carried a shaft 255. Secured to the shaft 255 is 65 a downwardly extending arm 257 and secured to the left-hand end of the shaft is a depending lever 259, the lower end of which is pivotally connected to the rear end of a bar 261 which extends forward and carries at its front end a 70 block 263. The bar 261 passes to the right of the left-hand bar 139 and is urged upward and rearward by a pull spring 265, the force of which is only just sufficient to hold the bar 261 up against its own weight and the weight of the block 263. 75

The arm 257 carries a lug 267 which, at times, cooperates with a pin 269 carried by an arm 271 secured to the left-hand end of the shaft 119.

The mechanism just described operates in the following manner. At the conclusion of the nail-driving cycle, the bars 139 rise and at this stage, the arm 223 rests on the stop surface 238 under the action of its own weight, the weight of the arm 221 and the tension of the spring 233, the lug 235 being in contact with the pin 237 and the hook 247 being below the pin 249. Since the treadle 135 is not depressed, the shaft 119 occupies a counterclockwise position, as viewed in Fig. 4, and the bar 261 is held rearward by the action of the spring 265, with the lug 267 in contact with the pin 269. In this position, the block 263 is above the rounded top surface 273 of a block 275 secured to the left-hand bar 139 and the block 263 abuts against the under side of a forward part of the arm 221 under the action of the spring 265.

As the bars 139 rise, the block 275 strikes against the under side of the block 263, after which further upward movement of the bars 139 causes the shaft 39 to rock in a counterclockwise direction to lift the stem 97 and, consequently, cause the boss 95 to be thrust up through the aperture 163 to free the heel from the mold. The lever 227, 229 is also rocked counterclockwise to some extent.

After the machine has stopped, the bars 139 are pushed rearward to afford access to the mold, the left-hand bar 139 abutting against the pin 231 and turning the lever 227, 229 counterclockwise a short distance relatively to the arm 221, until the hook 247 engages the pin 249, whereupon the lever 227, 229 and the arm 221 turn counterclockwise together to lift the heel still further in the mold. After the heel has been removed, the arm 241 is depressed, freeing the pin 249 from the hook 247 and allowing the nail block 93 to drop so that a new pile of lifts may be assembled in the mold. The hook 245 serves as a safeguard to prevent the pin 249 from getting behind the arm 243. When a new pile of lifts has been assembled in the mold, the bars 139 are drawn forward and, with them, the bar 261, the block 275 engaging the rear end of the block 263, which latter had slipped off the forward end of the surface 273 when the bars 139 were swung rearward so that the arm 221 might drop when the hand piece 241 was depressed. The parts are now in the positions shown in Fig. 4.

The treadle 135 is now depressed, swinging the arm 271 forward until the pin 269 abuts the lug 267, with the block 263 in its forward position and holds the block in this position. As a result of the block 263 being held forward, the blocks 275, 263 do not co-operate during the pricking cycle of operation of the machine and there is no actuation of the arm 221 at the end of this cycle. However, when the treadle 135 is released prior to the nail-driving cycle, the block 263 may move rearward into its position above the surface 273, which it does as soon as the block 275 has been lowered sufficiently.

The arm 203 has integral therewith a handle 277, by depression of which the arm may be swung relatively to the lever 127 until the play at 211 has been taken up. When this is done, a spring-pressed plunger 279 carried by the arm 129

engages in a recess in the arm 203 and holds the arm against clockwise movement relative to the arm 129, as viewed in Fig. 6, against the action of the spring 213.

The arrangement is such that when this occurs, the stop piece 205 is too high for the pin 217 to pass rearward over it, even when the slide 13 is in its forward position and, consequently, the machine cannot be started. However, when the slide 13 is in its rearward position, the stop piece 205 is sufficiently high to allow the pin 217 to pass forward or rearward beneath it so that the machine may be started repeatedly with the slide in nail-driving position. The handle 277 may thus be depressed and the spring-pressed plunger 279 allowed to become operative when it is desired to use the machine only for nail driving whereas, when it is desired to use the machine for pricking, the plunger 279 is withdrawn from the recess in the arm 203 and retained in withdrawn position by any suitable means (not shown).

Having described the invention, what is claimed as new and desired to be secured by Letters Patent of the United States is:

1. In a heel building machine, the combination of nail driving means and pricking means alternatively movable into operative position, power mechanism for actuating said means, and means for preventing the operator from starting said power mechanism when the pricking means is in operative position.

2. In a heel building machine, the combination of a heel mold, a gang of nail drivers and a gang of awls alternatively movable into line with the mold, a power driven actuator constructed and arranged to operate the gang of tools which is in line with the mold, and operator controlled means for preventing the application of power when the awls are in line with the mold.

3. In a heel building machine, the combination of a heel mold, a power driven actuator in line with the mold, a slide carrying a gang of nail drivers and a gang of awls, said slide being manually movable to place either the drivers or the awls between the mold and said actuator, and automatic means for preventing the application of power when neither the drivers nor the awls are in line with the mold.

4. In a heel building machine, the combination of a heel mold, a power operated actuator plunger, a slide carrying nail drivers and pricking awls which are alternatively movable into line with said mold and plunger, an operating shaft for moving the slide, a starting handle for controlling the application of power to said plunger, and a stop piece on said shaft constructed and arranged to prevent operation of the starting handle when neither the awls nor the drivers are in line with the mold.

5. In a heel building machine as defined in claim 4, a lost motion connection between the stop piece and the slide operating shaft, and a detent for holding the stop piece on the shaft in such a position relatively to the starting handle that said handle can be operated only when the nail drivers on the slide are in line with the mold.
